(57) **CLAIM**

The ornamental design for a construction toy component, as shown and described.

DESCRIPTION

FIG. 1 is a top perspective view of a first embodiment of the construction toy component;

FIG. 2 is a top plan view of the construction toy component of FIG. 1;

FIG. 3 is a first side elevational view of the construction toy component of FIG. 1;

FIG. 4 is a bottom plan view of the construction toy component of FIG. 1;

FIG. 5 is a second side elevational view of the construction toy component of FIG. 1;

FIG. 6 is a first end elevational view of the construction toy component of FIG. 1;

FIG. 7 is a second end elevational view of the construction toy component of FIG. 1;

FIG. 8 is a top perspective view of a second embodiment of the construction toy component;

FIG. 9 is a top plan view of the construction toy component of FIG. 8;

FIG. 10 is a first side elevational view of the construction toy component of FIG. 8;

FIG. 11 is a bottom plan view of the construction toy component of FIG. 8;

FIG. 12 is a second side elevational view of the construction toy component of FIG. 8;

FIG. 13 is a first end elevational view of the construction toy component of FIG. 8;

FIG. 14 is a second end elevational view of the construction toy component of FIG. 8;

FIG. 15 is a top plan view of the construction toy component of FIG. 1, shown in a first alternative configuration;

FIG. 16 is a top plan view of the construction toy component of FIG. 1 shown in a second alternative configuration; and,

FIG. 17 is a top plan view of the construction toy component of FIG. 1, shown in a third alternative configuration.

The broken lines are intended to show environmental structure and form no part of the claimed design. The bottom forms no part of the claimed design.
